US0D1069991S

(12) **United States Design Patent** (10) **Patent No.:** **US D1,069,991 S**
(45) **Date of Patent:** **** Apr. 8, 2025**

(54) **FAUCET WATER PURIFIER**

(71) Applicant: **Junfeng Zhu**, Zhumadian Henan (CN)

(72) Inventor: **Junfeng Zhu**, Zhumadian Henan (CN)

(**) Term: **15 Years**

(21) Appl. No.: **29/925,365**

(22) Filed: **Jan. 24, 2024**

(51) **LOC (15) Cl.** **23-01**

(52) **U.S. Cl.**

USPC **D23/238**; D23/207; D23/209

(58) **Field of Classification Search**

USPC D23/207, 209, 238-244, 499; 210/409,
210/430

CPC B01D 35/04; B01D 35/33; B01D 35/1573

(57) **CLAIM**

The ornamental design for a faucet water purifier, as shown and described.

DESCRIPTION

FIG. 1 is a perspective view of a faucet water purifier showing the new design;

FIG. 2 is another perspective view thereof;

FIG. 3 is a front elevation view thereof;

FIG. 4 is a back elevation view thereof;

FIG. 5 is a left-side view thereof;

FIG. 6 is a right-side view thereof;

FIG. 7 is a top plan view thereof; and,

FIG. 8 is a bottom plan view thereof.

1 Claim, 8 Drawing Sheets
